UNITED STATES PATENT OFFICE.

MORRIS RELKIN, OF NEW YORK, N. Y.

DESIGN FOR A SPOON HOLDER OR SIMILAR ARTICLE.

Application filed April 12, 1923. Serial No. 5,799. Term of patent 3½ years.

To all whom it may concern:

Be it known that I, MORRIS RELKIN, a citizen of the United States, and resident of the city of New York, in the county of New York and State of New York, have invented a new, original, and ornamental Design for a Spoon Holder or Similar Article, of which the following is a specification, reference being had to the accompanying drawing, forming part thereof.

the ornamental horizontally extending edge of said attachment.

Figure 2 is a vertical section on the line 2—2 of Figure 1, showing particularly the outline of said attachment.

I claim:

The ornamental design for a spoon holder or similar article as shown.

Signed at New York, in the county of New York and State of New York, this 11th day of April, 1923.

MORRIS RELKIN.
